(57) **ABSTRACT**

A coin storage device includes: storage compartments that store therein coins by denomination; and screw-type conveying members, installed for the respective storage compartments, each of the screw-type conveying members including a shaft having an elongated shape and having an outer circumferential surface provided with a blade portion that protrudes radially outwards in a spiraling shape, and conveying coins toward a front side by being rotated in one direction about a central axis of the shaft. Further, each of the screw-type conveying members includes an actuating portion to move center of gravity of coins accumulated on the actuating portion up and down periodically as the screw-type conveying member is rotated about the central axis of the shaft.

COIN STORAGE DEVICE

CROSS-REFERENCE TO RELATED APPLICATION(S)

The present application claims priority to and incorporates by reference the entire contents of Japanese Patent Application No. 2018-062568 filed in Japan on Mar. 28, 2018.

BACKGROUND

The present disclosure relates to a coin storage device.

In the related art, a coin storage device has been disclosed in Japanese Laid-open Patent Publication No. 2017-72948. The coin storage device disclosed in Japanese Laid-open Patent Publication No. 2017-72948 includes storage compartments and screw-type conveying members.

The storage compartments are sections where the coins are stored by denomination. Each of the screw-type conveying members is installed correspondingly in the storage compartment, and includes a first screw element and a second screw element.

The first screw element includes a columnar first shaft portion the outer circumferential surface of which is provided with a first blade portion protruding radially outwards in a spiraling shape, and conveys coins to the front side by being rotated about the central axis of the first shaft portion.

The second screw element includes a columnar second shaft portion the outer circumferential surface of which is provided with a second blade portion protruding radially outwards in a spiraling shape, and conveys coins to the front side by being rotated about the central axis of the second shaft portion. The rear end of the second screw element is linked to the front end of the first screw element via a linking unit.

In such a coin storage device, each pitch formed by the second blade portion provided to the second screw element stores therein one coin having been conveyed by the first screw element, and, when a dispensing instruction is given, the second screw element is rotated, and dispenses the stored coin.

In the coin storage device described above, most of the coins stored in the storage compartment are accumulated on the screw-type conveying members (the first screw element). Therefore, if some of the coins are stored in an upright direction along one of the side walls of the storage compartment, a phenomenon, what may be called “bridging”, may occur, in which the coins are accumulated so as to be bridged between the one side wall and the other side wall.

Once such bridging occurs, the blade portion (first blade portion) of the screw-type conveying member may be prevented from being brought into contact with the coins, even if the screw-type conveying member is rotated about the central axis of the shaft, and may cause the coins to jam in the storage compartment, and result in a failure to dispense the coins stored in the storage compartment.

SUMMARY

There is a need for providing a coin storage device capable of preventing jamming of coins in the storage compartments.

According to an embodiment, a coin storage device includes: storage compartments that store therein coins by denomination; and screw-type conveying members, installed for the respective storage compartments, each of

the screw-type conveying members including a shaft having an elongated shape and having an outer circumferential surface provided with a blade portion that protrudes radially outwards in a spiraling shape, and conveying coins toward a front side by being rotated in one direction about a central axis of the shaft. Further, each of the screw-type conveying members includes an actuating portion to move center of gravity of coins accumulated on the actuating portion up and down periodically as the screw-type conveying member is rotated about the central axis of the shaft.

BRIEF DESCRIPTION OF THE DRAWINGS

FIG. 1 is a perspective view illustrating an internal structure of a coin processor including a coin storage device according to an embodiment of the present disclosure;

FIG. 2 is a perspective view illustrating the coin storage device of FIG. 1;

FIG. 3 is a plan view illustrating the main part of the coin storage device illustrated in FIG. 1;

FIG. 4 is a plan view illustrating a main part of the storage compartment positioned on the rightmost side illustrated in FIGS. 2 and 3;

FIG. 5 is a perspective view illustrating a screw-type conveying member of FIG. 4;

FIG. 6 is a vertical cross-sectional view of the screw-type conveying member of FIG. 5;

FIG. 7 is an enlarged perspective view illustrating a main part of the screw-type conveying member of FIG. 5;

FIG. 8 is an enlarged vertical cross-sectional view illustrating a main part of the screw-type conveying member of FIG. 5;

FIG. 9 is a perspective view illustrating a conveying base portion of FIG. 5;

FIG. 10 is a perspective view illustrating the screw-type conveying member of FIG. 4;

FIG. 11 is a front view illustrating a main part of the storage compartment of FIG. 4;

FIG. 12 is an enlarged plan view illustrating a main part of the coin storage device of FIG. 3;

FIG. 13 is a schematic diagram illustrating a control system characterizing the coin storage device according to an embodiment of the present disclosure;

FIG. 14 is a flowchart illustrating a screw conveying control process executed by a storage control unit of FIG. 13;

FIG. 15 is a view illustrating an operation of the conveying base portion provided to a rear end section of the screw-type conveying member;

FIG. 16 is another view illustrating the operation of the conveying base portion provided to the rear end section of the screw-type conveying member;

FIG. 17 is a perspective view illustrating a modified example of the screw-type conveying member of FIG. 5;

FIG. 18 is a perspective view illustrating the conveying base portion of FIG. 17;

FIG. 19 is a front view illustrating the conveying base portion of FIG. 17; and

FIG. 20 is an enlarged perspective view illustrating a main part of the screw-type conveying member of FIG. 17.

DETAILED DESCRIPTION

A coin storage device according to a preferred embodiment of the present disclosure will be described in detail with reference to the accompanied drawings.

FIG. 1 is a perspective view illustrating an internal structure of a coin processor including a coin storage device according to an embodiment of the present disclosure. A coin processing device 1, herein explained as an example, is used as a change dispensing machine in a store such as a supermarket or a convenience store, for example, and includes a coin separating device 2, a coin inspecting device 3, a coin conveying device 4, and a coin storage device 10.

The coin separating device 2 supplies the coins deposited through a money payment port 1a in a manner that the coins are separated one by one. The coin inspecting device 3 determines the authenticity and the denominations of the coins supplied from the coin separating device 2, and supplies authentic coins to the coin conveying device 4. The coin conveying device 4 conveys the coins (authentic coins) supplied from the coin inspecting device 3 along a conveying path, sorts the coins by denomination, and supplies the sorted coins to the coin storage device 10. The coin storage device 10 stores therein the coins by denomination, and dispenses coins into a money reception port 1b in response to a dispensing instruction.

The coin storage device 10 that is a characterizing part of the present disclosure will now be explained. Both FIGS. 2 and 3 illustrate the coin storage device 10 of FIG. 1. However, FIG. 2 is a perspective view, and FIG. 3 is a plan view illustrating a main part.

As illustrated in FIGS. 2 and 3, the coin storage device 10 has a structure in which a plurality of (for example, six, in the illustrated example) storage compartments 11 are arranged side by side. In other words, the coin storage device 10 has a structure in which the storage compartments 11 are provided for storing, for example, 50-yen coins, 5-yen coins, 500-yen coins, 100-yen coins, 1-yen coins, and 10-yen coins in a manner arranged in this order from the left side. All of the storage compartments 11 included in the coin storage device 10 have the same structure except their lengths in the left-to-right direction. Therefore, in the description below, the storage compartment 11 positioned on the rightmost side will be explained, and thus, the explanations of the other storage compartments 11 will be omitted.

FIG. 4 is a plan view illustrating a main part of the storage compartment 11 of FIGS. 2 and 3 positioned on the rightmost side. As also illustrated in FIG. 4, the storage compartment 11 includes a screw-type conveying member 20 and a plurality of auxiliary screw members 30 all of which are disposed between a pair of left and right storage compartment guides 12.

As illustrated in FIG. 5, the screw-type conveying member 20 has an elongated shape with its longitudinal direction extending along the front-and-back direction, and includes a conveying portion 21 and a conveying base portion 22.

The conveying portion 21 includes a conveying shaft 21a that extends in the front-and-back direction, and the outer circumferential surface of which is provided with a blade portion 21b protruding radially outwards in a spiraling shape. Such a conveying portion 21 is formed by connecting a plurality of conveying elements 211. More specifically, the conveying portion 21 is formed by connecting the conveying elements 211 each of which has a size equal to or less than the pitch formed by the blade portion 21b when a core 23 is inserted into the conveying elements 211, as illustrated in FIG. 6, and the blade portion 21b is formed by connecting blade portion elements 211b that are provided to the conveying elements 211. The conveying elements 211 are connected to one another by inserting connecting protrusions 211c that are provided on one conveying element 211

into corresponding connecting recesses 211d provided on another conveying element 211.

The pitch, which is formed by the blade portion 21b, is a pitch formed by the adjacent blade portions 21b, viewing the screw-type conveying member 20 from one direction, e.g., from above, and is set to a size preventing a plurality of coins to fit inside.

In the conveying portion 21, in a border part between one blade portion element 211b and another blade portion element 211b together forming the blade portion 21b, a front side stepped portion 212 is formed in such a manner that the front surface of the blade portion element 211b positioned on the rear side protrudes toward the front side with respect to the front surface of the blade portion element 211b positioned on the front side, as illustrated in FIG. 7. Furthermore, a rear side stepped portion 213 is formed in such a manner that the rear surface of the blade portion element 211b positioned on the front side protrudes further toward the rear side with respect to the rear surface of the blade portion element 211b positioned on the rear side.

In the conveying portion 21, as illustrated in FIG. 8, the blade portion 21b (blade portion element 211b) has a cross-sectional shape in which the width in the front-and-back direction becomes greater as the positions separate from the conveying shaft 21a.

The conveying base portion 22 is provided on the rear end side of the conveying portion 21. The core 23 serving as the central axis of the conveying portion 21 is inserted into the conveying base portion 22, and an engaging projection 211e of the conveying element 211 positioned on the rearmost end is inserted into and engaged with an engaging recess 22a of the conveying base portion 22, so that the conveying base portion 22 is engaged with the conveying portion 21 and the screw-type conveying member 20 is formed thereby. In other words, the conveying base portion 22 can be integrally rotated with the conveying portion 21, about the core 23 as a common central axis that is shared between the conveying base portion 22 and the conveying portion 21.

Such a conveying base portion 22 includes a base end shaft 221 and an actuating portion 222, as illustrated in FIG. 9. The base end shaft 221 is a part that serves as the shaft 20a of the screw-type conveying member 20 together with the conveying shaft 21a of the conveying portion 21, in a configuration in which the conveying base portion 22 is engaged with the conveying portion 21, and extends along the front-and-back direction. This base end shaft 221 has the same outer diameter as that of the conveying shaft 21a.

The actuating portion 222 is provided on the outer circumferential surface of the base end shaft 221, in a manner protruding radially in directions orthogonal to the longitudinal direction (front-and-back direction) of the base end shaft 221. This actuating portion 222 includes an actuating outer circumferential surface 222a, positioned radially more outwards than the blade portion 21b, and an actuating surface 222b, that is planar and is continuous to the actuating outer circumferential surface 222a, as illustrated in FIG. 10 as well. This actuating surface 222b is a plane including a line tangent to the base end shaft 221 (shaft 20a).

In the screw-type conveying member 20 including an engagement of the conveying portion 21 and the conveying base portion 22, the conveying base portion 22 that is the rear end is connected to a motor 24 via a connecting unit (not illustrated). The motor 24 is driven in response to an instruction given by a storage control unit 50, which will be described later, and is enabled to rotate forwardly and reversely. When the motor 24 is driven forwardly, the screw-type conveying member 20 is rotated in one direction

(e.g., in the counterclockwise direction in a view from the rear side) about the central axis of the shaft 20a (the conveying shaft 21a and the base end shaft 221), and conveys the coins toward the front side. When the motor 24 is driven reversely, the screw-type conveying member 20 is rotated in the other direction about the central axis of the shaft 20a (e.g., in the clockwise direction in the view from the rear side), and conveys the coins toward the rear side.

Such a screw-type conveying member 20 stores therein coins in a stacked manner, in a rear end section that is behind a reverse roller 25 (see FIGS. 3 and 4), but stores one coin in each of the pitches formed by the blade portion 21b, in a front end section that is in front of the reverse roller 25.

The reverse roller 25 extends along the left-and-right direction in a manner extending over the storage compartments 11, and is rotatable about the central axis thereof. Such a reverse roller 25 is linked to the motor 24 via a linking unit 26 (see FIG. 3), and is caused to rotate by being driven by the motor 24. When the reverse roller 25 is rotated about the central axis, the reverse roller 25 is brought into contact with the coins being carried by the screw-type conveying member 20 toward the front side, so that the coins are stored in the respective pitches formed by the blade portion 21b.

As illustrated in FIG. 4, the auxiliary screw members 30 are provided in the rear end section that is behind the reverse roller 25, as a pair on the left and the right sides, in the left and the right space of the corresponding screw-type conveying member 20. These auxiliary screw members 30 are wound in a spiral shape, and, as illustrated in FIG. 11, are meshed with the blade portion 21b, with the central axes thereof positioned at a level higher than the central axis of the screw-type conveying member 20.

Such auxiliary screw members 30 are rotated about the respective central axes, when the screw-type conveying member 20 is rotated about the central axis of the shaft 20a, by being driven by the rotation of the screw-type conveying member 20.

Restricting guides 31 are provided on an upper area of the auxiliary screw members 30. The restricting guides 31 are provided in a manner protruding from the corresponding storage compartment guide 12 toward the screw-type conveying member 20, as illustrated in FIG. 12, and restricts upward movements of the auxiliary screw members 30 so as to prevent the auxiliary screw members 30 from becoming unmeshed from the screw-type conveying member 20.

Such restricting guides 31 are disposed in the manner described below. Specifically, the restricting guides 31 for the left auxiliary screw member 30 are disposed at positions facing where the restricting guides 31 for the right auxiliary screw member 30 are not provided, and the restricting guides 31 for the right auxiliary screw member 30 are disposed at positions facing where the restricting guides 31 for the left auxiliary screw member 30 are not provided. In other words, the restricting guides 31 for one of the auxiliary screw members 30 are disposed at positions facing where the restricting guides 31 for the other auxiliary screw member 30 are not provided.

FIG. 13 is a schematic diagram illustrating a control system including the coin storage device 10 according to an embodiment of the present disclosure. As illustrated in FIG. 13, the coin storage device 10 includes, besides the components described above, passage sensors 41 and a storage control unit (control unit) 50.

The passage sensors 41 are formed by optical sensors, for example, and are provided with the respective storage compartments 11, as illustrated in FIG. 2. Each of the passage

sensors 41 detects the coins supplied from the coin conveying device 4 into the corresponding storage compartment 11, and the detection result is sent to the storage control unit 50, as a passage signal.

5 The storage control unit 50 comprehensively controls the operations of the coin storage device 10, based on a computer program and data stored in a memory 55, and includes an input processing unit 51, a driving determining unit 52, and an output processing unit 53.

10 The storage control unit 50 may be implemented by causing a processor such as a Central Processing Unit (CPU) to execute a computer program, that is, by software, implemented by hardware such as an Integrated Circuit (IC), or may be implemented as a combination of software and hardware. This storage control unit 50 controls each of the storage compartments 11 individually.

15 The input processing unit 51 receives an input of a passage signal given from the passage sensors 41. The input processing unit 51 also receives an input of an instruction (such as a dispensing instruction or a stop instruction) given by a main control unit 42 comprehensively controlling the operations of the coin processing device 1.

20 The driving determining unit 52 determines whether a reverse driving condition is satisfied, when a passage signal is received via the input processing unit 51. The reverse driving condition is stored in the memory 55, and specifies whether the number of coins stored in the storage compartment 11 is equal to or greater than a predetermined number (threshold). In other words, the driving determining unit 52 adds the number of coins remaining in the storage compartment 11 since when the coins are dispensed last time, to the number of coins supplied into the storage compartment 11, and determines that the reverse driving condition is satisfied if the resultant sum is equal to or greater than the threshold.

25 The output processing unit 53 controls driving and the like the motor 24, by outputting a driving instruction (a forward driving instruction or a reverse driving instruction) and a driving stop instruction (a forward driving stop instruction or a reverse driving stop instruction) to the motor 24.

30 In the coin storage device 10 having such a structure, when the storage control unit 50 receives an input of a dispensing instruction given by the main control unit 42 via the input processing unit 51, the storage control unit 50 sends a forward driving instruction to the motor 24 via the output processing unit 53. This causes the screw-type conveying member 20 to rotate in one direction (e.g., in the counterclockwise direction in a view from the rear side) about the central axis of the shaft 20a (the conveying shaft 21a and the base end shaft 221). As a result, in the front end section of the screw-type conveying member 20, a predetermined number of coins, stored in the corresponding pitch formed by the blade portion 21b, are conveyed toward the front side, and dispensed into a dispensed coin conveyor 5 (see FIGS. 2 and 3). As a result, the coins are dispensed from the dispensed coin conveyor 5 into the money reception port 1b. By driving the motor 24 in the forward direction in the manner described above, some of the coins accumulated in the rear end section of the screw-type conveying member 20 are conveyed toward the front side, and are stored as preparatory money in the front end section of the screw-type conveying member 20 by the operation of the reverse roller 25, with each of such coins stored in the corresponding pitch formed by the blade portion 21b.

35 In the coin processing device 1, when a plurality of coins are deposited via the money payment port 1a, the coin separating device 2 separates the coins one by one, and the

coin inspecting device **3** differentiates the coins supplied from the coin separating device **2** based on the authenticity and the denominations of the coins, and supplies the authentic coins into the coin conveying device **4**. The coin conveying device **4** then conveys the coins supplied from the coin inspecting device **3** (the authentic coins) along the conveying path, classifies the coins by denomination, and supplies the classified coins into the coin storage device **10**. As a result, the storage control unit **50** executes a screw conveying control process as described below.

FIG. 14 is a flowchart illustrating the screw conveying control process performed by the storage control unit **50** of FIG. 13.

In the screw conveying control process, if a passage signal is input via the input processing unit **51** (Yes in Step S101), the storage control unit **50** causes the driving determining unit **52** to determine whether a reverse driving condition is satisfied (Step S102). In other words, the storage control unit **50** causes the driving determining unit **52** to add the number of coins remaining in the storage compartment **11** since when the coins are disposed last time to the number of supplied coins, and to determine whether the resultant sum is equal to or greater than the threshold.

If it is determined that the reverse driving condition is not satisfied (No in Step S102), the process goes back to the beginning without performing the process described below, and ends. In this case, more coins can be supplied into and stored in the rear end section of the screw-type conveying member **20**.

If it is determined that the reverse driving condition is satisfied (Yes in Step S102), the storage control unit **50** sends a reverse driving instruction to the motor **24** via the output processing unit **53**, and drives the motor **24** reversely (Step S103).

In response, the screw-type conveying member **20** is rotated in the other direction about the central axis of the shaft **20a** (e.g., in the clockwise direction in the view from the rear side), and conveys the coins toward the rear side. In this manner, because the screw-type conveying member **20** is rotated in the other direction about the central axis of the shaft **20a**, the coins accumulated in the rear end section of the screw-type conveying member **20** are also conveyed to the rear side.

Because the conveying base portion **22** that is the rear end of the screw-type conveying member **20** has the actuating portion **222** that includes the actuating outer circumferential surface **222a**, positioned radially more outwards than the blade portion **21b**, and the actuating surface **222b**, that is a plane continuous to the actuating outer circumferential surface **222a** and including a line tangent to the base end shaft **221** (shaft **20a**), so that the actuating surface **222b** and the actuating outer circumferential surface **222a** are brought into contact with the coins alternately. In this manner, the actuating portion **222** can move the center of gravity of the coins accumulated on the actuating portion **222** up and down periodically.

In particular, even if some of the coins **C** become stored in the upright direction along the left storage compartment guide **12**, and a phenomenon what is called "bridging" occurs, in which the coins **C** are accumulated so as to be bridged between the right and the left storage compartment guides **12** as illustrated in FIGS. 15 and 16, such bridging can be resolved by causing the actuating portion **222** to move the center of gravity of the coins **C** accumulated on the actuating portion **222** up and down periodically.

If the storage control unit **50** then inputs a stop instruction given by the main control unit **42** via the input processing

unit **51** (Yes in Step S104), the storage control unit **50** sends a reverse driving stop instruction to the motor **24** via the output processing unit **53**, and stops driving the motor **24** reversely (Step S105). Then, the process goes back to the beginning, and ends.

Through the process, the coins accumulated in the rear end section of the screw-type conveying member **20** inside of the storage compartment **11** can be evenly distributed across the entire rear end section, and it is possible to prevent the coins from being gathered on the front end side of the rear end section.

As explained above, with the coin storage device **10** according to the embodiment of the present disclosure, when the screw-type conveying member **20** is rotated in the other direction about the central axis of the shaft **20a**, the actuating portion **222** provided to the rear end of the screw-type conveying member **20** moves the center of gravity of the coins accumulated on the actuating portion **222** up and down periodically. Therefore, what is called "bridging" can be eliminated, so that it is possible to prevent jamming of the coins in the storage compartment **11**.

According to the coin storage device **10** described above, when the screw-type conveying member **20** is rotated about the central axis of the shaft **20a**, the auxiliary screw members **30**, meshed with the blade portion **21b**, are caused to rotate about their respective central axes, by being driven by the rotation of the screw-type conveying member **20**, in the space on the respective left and right sides of the rear end section of the screw-type conveying member **20** of the storage compartment **11**. Therefore, it is possible to prevent the coin from being stuck between the screw-type conveying member **20** and each of the pair of the left and right storage compartment guides **12** that constitute the storage compartment **11**. Hence, it is possible to prevent jamming of the coins in the storage compartment **11**.

According to the coin storage device **10** described above, because the restricting guides **31** are provided for preventing the auxiliary screw members **30** from being unmeshed from the screw-type conveying member **20**, and the restricting guides **31** for one of the auxiliary screw members **30** are disposed at positions facing where the restricting guides **31** for the other auxiliary screw member **30** are not provided, it is possible to prevent the coins from being positioned in a manner bridged between the restricting guide **31** for the one auxiliary screw member **30** and the other restricting guide **31** for the other auxiliary screw member **30**. In this manner, the coins can be conveyed by rotating the screw-type conveying member **20**, and this configuration also serves to prevent jamming of the coins in the storage compartment **11**.

According to the coin storage device **10** described above, the conveying portion **21** of the screw-type conveying member **20** includes a plurality of conveying elements **211** that are connected to one another. Therefore, it is possible to use a highly rigid material for the conveying elements **211**, to which a heavy load is applied, and use another material for the other conveying elements **211**. In other words, for example, it is possible to use a metal material for the conveying elements **211** positioned below the reverse roller **25**, and to use a resin material for the other conveying elements **211**. In this manner, the weight of the screw-type conveying member **20** can be reduced, compared with a configuration in which the entire screw-type conveying member is made of a metal material.

Moreover, in the conveying portion **21**, in a border part between the blade portion element **211b** and the blade portion element **211b** together forming the blade portion **21b**, the front side stepped portion **212** is formed in such a

manner that the front surface of the blade portion element 211b positioned on the rear side protrudes toward the front side with respect to the front surface of the blade portion element 211b positioned on the front side. Therefore, when the screw-type conveying member 20 is rotated about the central axis of the shaft 20a in one direction, it is possible to prevent the coin from being caught at the border part, and thus, the coins can be conveyed smoothly toward the front side. Furthermore, because the rear side stepped portion 213 is formed in such a manner that the rear surface of the blade portion element 211b positioned on the front side protrudes further toward the rear side with respect to the rear surface of the blade portion element 211b positioned on the rear side. Therefore, when the screw-type conveying member 20 is rotated about the central axis of the shaft 20a in the other direction, it is possible to prevent the coin from being caught at the border part, and the coins can be conveyed smoothly toward the rear side.

Furthermore, in the conveying portion 21, the blade portion 21b (the blade portion element 211b) has a cross-sectional shape in which the width in the front-and-back direction becomes greater toward the tip positioned as the position of the width is separated from the conveying shaft 21a. Therefore, when the screw-type conveying member 20 is rotated about the central axis of the shaft 20a in one direction, the tip of the blade portion 21b and the entire surface of a part above the conveying shaft 21a can be brought into contact with the coin. Therefore, the coin can be conveyed smoothly.

FIG. 17 is a perspective view illustrating a modified example of the screw-type conveying member 20 of FIG. 5. The elements that are the same as those in the screw-type conveying member 20 described above are given the same reference numerals, and explanations thereof will be omitted as appropriate.

A screw-type conveying member 20' explained herein as the modified example has an elongated shape with its longitudinal direction extending along the front-and-back direction, and includes the conveying portion 21 and a conveying base portion 22'.

The conveying base portion 22' is provided on the rear end side of the conveying portion 21. The conveying base portion 22' is inserted in the core 23 serving as the central axis of the conveying portion 21, and the engaging projection 211e of the conveying element 211 positioned on the rearmost end is inserted into and engaged with the engaging recess 22a of the conveying base portion 22', so that the conveying base portion 22' is engaged with the conveying portion 21, and the screw-type conveying member 20' is constituted thereby. In other words, the conveying base portion 22' can be rotated integrally with the conveying portion 21 about the core 23 as a common central axis that is shared between the conveying base portion 22' and the conveying portion 21.

Such a conveying base portion 22' includes the base end shaft 221 and an actuating portion 223 as illustrated in FIG. 18. The base end shaft 221 is a part that serves as the shaft 20a of the screw-type conveying member 20' together with the conveying shaft 21a of the conveying portion 21 in a configuration in which the conveying base portion 22' is engaged with the conveying portion 21, and extends along the front-and-back direction. This base end shaft 221 has the same outer diameter as the conveying shaft 21a.

The actuating portion 223 is provided on the outer circumferential surface of the base end shaft 221, in a manner protruding radially in a direction orthogonal to the longitudinal direction (front-and-back direction) of the base end

shaft 221. This actuating portion 223 has an actuating outer circumferential surface 223a positioned radially more outwards than the blade portion 21b, and an actuating surface 223b that is curved and continuous to the actuating outer circumferential surface 223a.

Such an actuating surface 223b has a shape that is twisted more in one direction about the central axis of the base end shaft 221 (the shaft 20a) (e.g., in the counterclockwise direction in a view from the rear side) as the actuating surface 223b extends further toward the front side from a rear end 223b1 that includes a line tangent to the base end shaft 221 as illustrated in FIG. 19. The angle formed by the rear end 223b1 and a front end 223b2 of the actuating surface 223b is set to 25 degrees to 45 degrees, for example, in a view from the front side. The front end 223b2 is positioned in the other direction with respect to a rear end 21b1 of the blade portion 21b (the blade portion element 211b) about the central axis of the shaft 20a (e.g., in the clockwise direction in the view from the rear side) as illustrated in FIG. 20.

In the screw-type conveying member 20' including the engagement of the conveying portion 21 and the conveying base portion 22', the conveying base portion 22', that is the rear end, is connected to the motor 24 via a connecting unit (not illustrated). When the motor 24 is driven forwardly, the screw-type conveying member 20' is rotated in one direction (e.g., in the counterclockwise direction in a view from the rear side) about the central axis of the shaft 20a (the conveying shaft 21a and the base end shaft 221), and conveys the coins toward the front side. When the motor 24 is driven reversely, the screw-type conveying member 20' is rotated in the other direction (e.g., in the clockwise direction in the view from the rear side) about the central axis of the shaft 20a, and conveys the coins toward the rear side.

With such a configuration, when the screw-type conveying member 20' is rotated in the other direction (e.g., in the clockwise direction in the view from the rear side) about the central axis of the shaft 20a, the actuating surface 223b and the actuating outer circumferential surface 223a are brought into contact with the coins alternately, so that the actuating portion 223 can move the center of gravity of the coins accumulated on the actuating portion 223 up and down periodically.

In particular, when some of the coins become stored in the upright direction along one of the storage compartment guides 12, and a phenomenon what is called bridging, in which the coins are accumulated in a manner straddled between such coins and the other storage compartment guide 12, occurs, such bridging can be resolved by causing the actuating portion 223 to move the center of gravity of the coins up and down periodically. Therefore, it is possible to prevent jamming of the coins in the storage compartment 11.

Furthermore, the actuating surface 223b has a shape that is twisted more in the one direction about the central axis (e.g., in the counterclockwise direction in a view from the rear side) of the base end shaft 221 (shaft 20a) as the actuating surface 223b extends further toward the front side from the rear end 223b1 including a line tangent to the base end shaft 221. Therefore, it is possible to displace the coins to the front side, while moving the coins up and down, when the screw-type conveying member 20' is rotated in the other direction (e.g., in the clockwise direction in the view from the rear side) about the central axis of the shaft 20a. Hence, it is possible to prevent the coins from being caught by and locked onto the actuating surface 223b. This configuration also can prevent jamming of the coins in the storage compartment 11. Furthermore, because the front end 223b2 is

11

positioned in the other direction (e.g., in the clockwise direction in the view from the rear side) with respect to the rear end **21b1** of the blade portion **21b** (blade portion element **211b**) about the central axis of the shaft **20a**, the actuating surface **223b** can be brought into contact with the coins more reliably than the blade portion **21b** does, when the screw-type conveying member **20** is rotated in the other direction (e.g., in the clockwise direction in the view from the rear side) about the central axis of the shaft **20a**.

A preferred embodiment of the present disclosure and a modification thereof are explained above, but the present disclosure is not limited thereto, and various modifications are still possible.

In the embodiment described above, the actuating portion **222** is configured to move the center of gravity of the coins accumulated on the actuating portion **222** up and down periodically as the screw-type conveying member **20** is rotated in the other direction about the central axis of the shaft **20a**. However, according to the present disclosure, the actuating portion may be configured in any way as long as the actuating portion can move the center of gravity of the coins accumulated on the actuating portion up and down periodically as the screw-type conveying member is rotated about the central axis of the shaft.

In the embodiment described above, the actuating portion **222** includes the actuating outer circumferential surface **222a** that is positioned radially more outwards than the blade portion **21b**, and the actuating surface **222b** that is a plane continuous to the actuating outer circumferential surface **222a** and including a line tangent to the base end shaft **221** (shaft **20a**). However, according to the present disclosure, the configuration of the actuating portion is not limited thereto, and any other configuration is included in the present disclosure as long as the actuating portion can move the center of gravity of the coins accumulated on the actuating portion up and down periodically as the screw-type conveying member is rotated about the central axis of the shaft.

In the embodiment described above, the reverse driving condition, satisfaction of which is determined by the driving determining unit **52**, is explained to specify that the number of coins stored in the storage compartment **11** is equal to or greater than a predetermined number (threshold). However, according to the present disclosure, the reverse driving condition is not limited thereto, and the reverse driving condition may specify that the number of coins continuously supplied into the storage compartment is equal to or greater than a preset number.

According to the present disclosure, because the actuating portion provided to the screw-type conveying member moves the coins accumulated on the actuating portion up and down periodically as the screw-type conveying member is rotated about the central axis of the shaft, what is called "bridging" can be resolved. Therefore, it is possible to obtain an effect to prevent jamming of the coins in the storage compartments.

Although the disclosure has been described with respect to specific embodiments for a complete and clear disclosure, the appended claims are not to be thus limited but are to be construed as embodying all modifications and alternative constructions that may occur to one skilled in the art that fairly fall within the basic teaching herein set forth.

What is claimed is:

1. A coin storage device comprising:
storage compartments that store therein coins by denomination; and

12

screw-type conveying members, installed for the respective storage compartments, each of the screw-type conveying members including a shaft having an elongated shape and having an outer circumferential surface provided with a blade portion that protrudes radially outwards in a spiraling shape, and configured to convey coins toward a front side by being rotated in one direction about a central axis of the shaft, wherein

each of the screw-type conveying members includes an actuating portion configured to move center of gravity of coins accumulated on the actuating portion up and down periodically as the screw-type conveying member is rotated about the central axis of the shaft.

2. The coin storage device according to claim 1, wherein the actuating portion is configured to move the center of gravity of the coins accumulated on the actuating portion up and down periodically as the screw-type conveying member is rotated in another direction about the central axis of the shaft.

3. The coin storage device according to claim 2, wherein the actuating portion is provided to an outer circumferential surface of the shaft in a manner protruding radially in directions orthogonal to a longitudinal direction of the shaft, and

the actuating portion includes:

an actuating outer circumferential surface that is positioned radially more outwards than the blade portion; and

an actuating surface that is planar and is continuous to the actuating outer circumferential surface.

4. The coin storage device according to claim 3, wherein the actuating surface is a plane including a line tangent to the shaft.

5. The coin storage device according to claim 2, wherein the actuating portion is provided to an outer circumferential surface of the shaft in a manner protruding radially in directions orthogonal to a longitudinal direction of the shaft, and

the actuating portion includes:

an actuating outer circumferential surface that is positioned radially more outwards than the blade portion; and

an actuating surface that is curved and is continuous to the actuating outer circumferential surface, and

the actuating surface has a shape that is twisted more in the one direction as the actuating surface extends further toward the front side from a rear end that includes a line tangent to the shaft.

6. The coin storage device according to claim 5, wherein the actuating surface has a shape in which a front end of the actuating surface is positioned in the other direction with respect to a rear end of the blade portion.

7. The coin storage device according to claim 1, wherein the actuating portion is provided to a rear end of the shaft.

8. The coin storage device according to claim 1, further comprising:

auxiliary screw members, installed in a manner meshed with the blade portion on both sides of the screw-type conveying member in the storage compartment, configured to rotate about respective central axes thereof, as the screw-type conveying member is rotated about the central axis of the shaft, by being driven by the rotation of the screw-type conveying member.

9. The coin storage device according to claim 8, wherein each of the auxiliary screw members is provided with a restricting guide that restricts the auxiliary screw member from being unmeshed from the screw-type conveying member, and

5

the restricting guide for one of the auxiliary screw members is disposed at a position facing where the restricting guide for another auxiliary screw member is not provided.
